UNITED STATES PATENT OFFICE.

CHRISTIAN C. WARTH, OF SPOKANE, WASHINGTON.

COLLAPSIBLE-TUBE CLOSURE.

Application filed April 2, 1925. Serial No. 29,166.

To all whom it may concern:

Be it known that I, CHRISTIAN C. WARTH, a citizen of the United States, residing at Spokane, in Spokane County, and State of Washington, have invented certain new and useful Improvements in Collapsible-Tube Closures, of which the following is a specification.

My present invention relates to improvements in collapsible tube closures for use in connection with containers and dispensers of this type in which paint, soap, dental cream, shaving cream and other similar materials are packed. The primary object of the invention is the provision of a closure of this type which is comparatively simple in construction and composed of a minimum number of parts and therefore comparatively inexpensive in cost of manufacture.

The closure contemplates a detachable cap hinged to the head of the tube in such manner that the tube is effectively closed when the cap is in place to prevent evaporation of moisture from the contents of the tube, and the detachable or removable cap may readily be displaced to completely uncover the mouth of the tube or outlet opening so that the contents of the tube may freely be dispensed when desired. Means are provided for retaining the cap in closed position under spring pressure, and means are also provided for holding the displaced cap in position out of the way when material is to be dispensed or squeezed from the tube, all as will hereinafter be more fully pointed out and claimed.

In the accompanying drawings I have illustrated one complete example of the physical embodiment of my invention wherein the parts are combined and arranged in accordance with the best mode I have thus far devised for the practical application of the principles of my invention.

Figure 1 is a view in elevation showing the upper portion of a collapsible tube with the closure of my invention applied thereto.

Figure 2 is a vertical sectional view through the closure and head of the tube.

Figure 3 is a top plan view of the closure showing in dotted lines the cap or closure in opened position.

The tube 1 illustrated in the drawings is of the usual type for collapsible containers for paints, dental, shaving or medical creams or pastes and similar materials, the

material of which the tube is composed readily adapting it to be rolled upon itself as the contents are ejected or dispensed therefrom.

The head 2 on the tube is rigid and provided with a throat or outlet passage 3, and on the top of the head is a circular tapered seat 4 surrounding the opening of the throat 3. A gasket or washer of suitable material, indicated as 5, is preferably used on the dished or tapered seat 4 to insure a close and uniform fit and seat for the closure in the form of a valve.

On the top of the tube head is mounted a cap 6 of rounded or circular shape and made up of suitable material. At its underside or bottom this cap is provided with a central conical valve head 7 of substantially the same diameter as the head 2 of the tube. The conical valve head is of less diameter than its cap and projects therefrom to seat against the top face of the gasket or washer 5 on the tube head. The valve head conforms to the shape of the valve seat and together these parts provide an effectual closure or seal for the contents of the tube, in such manner that the closure cannot be displaced without pressure thereon.

In the top portion of the cap 6 is fashioned a narrow recess 8 arranged diametrically of the cap with its ends terminating near the periphery of the cap, the lower end of the recess terminating above and being closed by the valve head 7 as shown in Figure 2.

At diametrically opposite points of the valve head are provided holes 9 and 10 that open at one end to the recess and at the other end open at the underside of the cap adjacent to the valve head, the longitudinal axis of these round holes being parallel with the outer face of the tube head as shown in Figure 2.

Within the recess of the cap I arrange the coil 11 of a retaining spring or U-shaped yoke and the valve head portion 7 of the cap is grooved as at 11^a to form a seat for this coil or loop. The retaining spring or U-shaped yoke is fashioned with parallel arms 12 and 13 that pass through the respective holes 9 and 10 of the cap and extend down alongside the upper portion of the tube head. At their ends these arms terminate in angularly arranged pivot pins 14 that are seated in transversely disposed

sockets 15 fashioned in the outer face of the tube head.

The coil 11 of the spring yoke is held under tension by the pins 14 when the latter are snapped into their sockets and this tension of the coil retains the valve head of the cap in its seat in the tube head. To remove the valve head from its seat the cap, which may be knurled as indicated in Figure 1, is grasped between a finger and thumb and pulled away from the tube head, against increased tension or compression of the spring coil. When the valve head has been removed sufficiently from its seat the cap is swung bodily on its pivot pins around the tube head to a position at right angles to its original closed position. The mouth of the tube head is thus uncovered and material may freely be dispensed therefrom.

For retaining the cap in open position and preventing it from wobbling I provide a pair of parallel grooves 16 arranged tangentially at the outer face of the tube head and intersecting the sockets 15, which grooves receive the arms 12 and 13 of the hinged yoke. It will be understood that the material of the yoke is resilient and the arms will snap into and out of the grooves as the cap is swung in either direction. To replace the cap it is swung around and at the same time pulled out from the tube head until the valve head is in position to be properly seated. Then when the pull on the cap is released the spring yoke returns the valve head to its seat.

Having thus fully described my invention what I claim as new and desire to secure by Letters Patent is—

1. The combination with a dispensing head having a valve seat and opposed sockets, of a

closure cap having a head to fit said seat, a yoke having a spring coil enclosed within a recess in said cap and its arms passed through holes in said cap, and angular pivot pins on the ends of said arms seated in said sockets.

2. The combination with a dispensing head having a valve seat, opposed sockets, and grooves intersecting said sockets, of a recessed closure cap having spaced holes 50 therein and a valve head on said cap, a yoke having a spring coil in the recessed head and arms located in said holes, and angular pivot pins on the ends of said arms seated in said sockets.

3. The combination with a dispensing head having a valve seat, opposed sockets and tangential grooves intersecting said sockets, of a closure cap having a head to fit said seat and provided with spaced holes 60 extending therethrough, said cap being recessed above said head, a spring yoke having a coil disposed in the recess of said cap bearing on said head and retained between the walls of the recess, flexible spring arms 65 on said yoke extending from said coil through said holes in the head, and angular pivot pins on the ends of said arms for engagement in the sockets of said dispensing head.

4. A tube closure comprising a cap of greater diameter than the tube and having a narrow longitudinal recess closed at the bottom, and a spring coil retained in said recess parallel with the walls thereof, the 75 ends of said coil being passed through said cap for attaching engagement with the sides of the tube.

In testimony whereof I affix my signature.
CHRISTIAN C. WARTH.
